CLAIM

The ornamental design for a mattress cover, as shown and described.

DESCRIPTION

FIG. 1 is a left elevation view of the mattress cover in a first embodiment, of which the right elevation view is a mirror image;

FIG. 2 is a rear elevation view of the mattress cover in the first embodiment, of which the front elevation view is a mirror image;

FIG. 3 is a left elevation view of the mattress cover in alternative embodiment of the first embodiment, of which the right elevation view is a mirror image;

FIG. 4 is a rear elevation view of the mattress cover in the alternative embodiment of the first embodiment, of which the front elevation view is a mirror image;

FIG. 5 is a left elevation view of the mattress cover in a further alternative embodiment of the first embodiment, of which the right elevation view is a mirror image; and, FIG. 6 is a rear elevation view of the mattress cover in the further alternative embodiment of the first embodiment, of which the front elevation view is a mirror image.

Portions drawn in broken lines represent parts of the mattress cover that form no part of the claimed design.
